DESIGN FOR AN OVEN CONTROL INDICATOR

Theodore E. Graves, Orange, N. J., assignor to The Wilcolator Company, Newark, N. J., a corporation of Delaware

Application July 11, 1941, Serial No. 102,038

Term of patent 14 years

To all whom it may concern:

Be it known that I, Theodore E. Graves, a citizen of the United States, residing at Llewellyn Park, Orange, New Jersey, and whose post-office address is c/o The Wilcolator Company, 17-23 Nevada Street, Newark, New Jersey, county of Essex, have invented a new, original, and ornamental Design for an Oven Control Indicator, of which the following is a specification, reference being had to the accompanying drawing, forming part thereof.

Figure 1 is a front view of an oven control indicator showing my new design, and

Figure 2 is a side view of the oven control indicator shown in Fig. 1.

The characteristic features of my design reside in the specific arrangement and association of the dial and pointer with the handle, as shown.

I claim:

The ornamental design for an oven control indicator, substantially as shown and described.

THEODORE E. GRAVES.
